UNITED STATES PATENT OFFICE.

LEON FRANK PARKHURST, OF PITTSFIELD, MASSACHUSETTS, ASSIGNOR TO GENERAL ELECTRIC COMPANY, A CORPORATION OF NEW YORK.

FLAT-IRON STAND.

1,010,518

Specification of Letters Patent.

Patented Dec. 5, 1911.

Application filed August 25, 1908. Serial No. 450,166.

To all whom it may concern:

Be it known that I, LEON FRANK PARKHURST, a citizen of the United States, residing at Pittsfield, county of Berkshire, State 5 of Massachusetts, have invented certain new and useful Improvements in Flat-Iron Stands, of which the following is a specification.

This invention relates to devices for supporting flat-irons and the like and has for 10 its object the provision of a device of this character whereby a flat-iron or similar tool may be supported in a simple and efficient manner.

15 One of the objects of my invention is to provide a flat-iron stand which is so arranged that the iron may be supported in the ordinary way with the face downward and which may also be inverted so that the 20 face of the iron may be utilized as a stove.

Another object of my invention is to provide a stand in which a minimum amount of heat is conducted to the table and in 25 which there are only a few points of contact to the iron and table.

Further objects of my invention will appear in the course of the following specification in which I have shown my invention embodied in concrete form for purposes 30 of illustration.

In the drawing, Figure 1 shows the stand supporting my flat-iron in the usual way; Fig. 2 shows the stand supporting the inverted iron; Fig. 3 is a plan view of my 35 device; and Fig. 4 is an end elevation of the same.

Referring to the drawing, 10 and 11 represent two plates which are spaced apart and arranged to support the face of the iron. 40 These plates are flanged outward from each other, preferably at the four edges. These flanged edges are provided with projecting points 12 and 13, the latter points making contact with the table. The center of each 45 plate is cut away at 14 and points 15 are arranged around the opening for supporting the face of the iron. Lightening holes 16 are provided as desired. These plates may be made and secured together in any 50 desired way. I have found that they can be made very rigid at a low cost by casting them with the spacing blocks 17 in one piece. The plates are preferably rectangu-

lar in shape and the spacing blocks are arranged at three of the corners. By omitting one of the spacing blocks the flat-iron handle 18 may be inserted between the plates as shown in Fig. 2 and the back of the iron supported by the edges of the plates. These edges are made wide enough so as to form 60 a supporting base for the plates when they stand on edge. Either side of the stand may be used to support the face of the iron, but when the iron is to be inverted, the corner of the stand without the spacing block 65 must be upward. The iron which is used in connection with this stand may be of any desired form.

When the iron is not in use, it may be placed on the stand in the usual way as 70 shown in Fig. 1 but when it is desired to use the flat-iron as a stove, the stand may be placed on edge and the handle of the iron inserted between the plates so that the back of the iron is supported by the flanges 75 on the plates as shown in Fig. 2.

While I have described my invention as constructed and arranged in a definite manner in accordance with the patent statutes, it should be understood that I do not limit 80 my invention thereto except in so far as it is limited by the scope of the claims annexed hereto.

What I claim as new and desire to secure by Letters Patent of the United States, is, 85

1. A flat iron stand comprising two rectangular supporting plates for the face of the iron and spacing blocks at three corners thereof for rigidly securing the plates in parallel relation to admit the handle of the 90 iron between the plates.

2. A flat iron stand comprising two rectangular supporting plates for the face of the iron provided with spacing blocks at three corners for securing the plates in parallel relation to admit a flat iron handle between them, said plates being flanged away 95 from each other so that the stand rests on the flanges in any position.

In witness whereof I have hereunto set 100 my hand this twenty first day of August, 1908.

LEON FRANK PARKHURST.
